(57) **CLAIM**

The ornamental design for a perimeter gutter having a curved section for a swimming pool, as shown and described.

DESCRIPTION

FIG. 1 is a perspective view of a perimeter gutter having a curved section for a swimming pool showing a preferred embodiment of the new design;

FIG. 2 is a transverse view of the perimeter gutter having a curved section for a swimming pool taken along lines 2—2 of FIG. 1, the other side being a mirror image thereof;

FIG. 3 is a top plan view of the perimeter gutter having a curved section for a swimming pool; and,

FIG. 4 is a longitudinal view of the perimeter gutter having a curved section for a swimming pool.
